UNITED STATES PATENT OFFICE.

JESSE E. HANCOCK, OF DU PONT, GEORGIA.

DUMPING GRATE.

Application filed June 7, 1923. Serial No. 643,903.

To all whom it may concern:

Be it known that I, JESSE E. HANCOCK, citizen of the United States, residing at Du Pont, in the county of Clinch and State of Georgia, have invented certain new and useful Improvements in Dumping Grates, of which the following is a specification.

This invention relates to dumping grates, such as are shown in my copending application, Serial Number 590,088, filed September 23, 1922, the said application having since become Patent Number 1,460,242 and has special reference to a novel arrangement for holding the dumping sections 15 yieldably against dumping movement at times, or in dumping position at other times.

One important object of the invention is to provide an improved and simplified 20 means whereby the dumping sections of grates of this character will be normally held in horizontal or fuel supporting position.

A second important object of the invention is to provide novel means whereby said sections may be locked in either horizontal or tilted position according to the wishes of the operator.

In this instance, the invention contemplates certain novel arrangements of yieldable supporting means and locking devices cooperating to produce the desired results, and such means will be hereinafter described in detail, illustrated in the drawings accompanying this specification, and set forth specifically in the matter claimed.

In these drawings, the same reference characters are used for the same parts throughout, and

Fig. 1 is a plan view of a dumping grate constructed in accordance with this invention, one of the grate sections being shown in horizontal position, and the other being tilted.

Fig. 2 is an end view thereof.

Fig. 3 is a perspective view of one form of lock for the tilting bar.

Fig. 4 is a perspective view of a second form of lock therefor.

Referring to the drawings, the numeral 10 indicates the main frame of the invention, and in this main frame are supported a pair of dumping sections 11, which are provided at their ends with journal portions 12 carried in bearings 13 on the underside of the frame 10. These bearings are ar-

ranged in alinement at the front and back portions of the frame so that the dumping sections dump laterally. Each of the journal sections are provided with a squared portion 14 whereon is fitted an arm 15 having a series of openings 16 therein. At each end of the frame 10, there is provided a centrally disposed bracket 17, and to each arm 15 is connected a spring 18 which has its remaining end connected to the bracket 17, the spring 18 being hooked into any one of the openings 16 according to the leverage and stress desired to be exerted on the arm 15. These ends 14 also carry levers 19 which are connected by links 20 with the lower ends of levers 21 extending upward to a suitable slot 22 in the deck 23 of the main frame. By the oscillation of the levers 21 in their respective slots, it will be 75 obvious that the dumping frames may be tilted against the action of the springs 18, these springs normally holding said frames horizontal, and this horizontal position is assured by reason of the upstanding ends of the levers 21 engaging against shoulders 24 formed by off-setting the ends of the slot 22.

In each of the forms shown, suitable keepers are provided whereby the levers may be locked in position either with the dumping sections 11 horizontal, or with the sections in dumping position, and in the form shown in Fig. 3, these keepers comprise each a hinge-like structure having a leaf 25 fixed to the deck 23, and a second leaf 26 notched as at 27 and foldable over the respective end of the slot 22, the arrangement being such that when the lever 21 is held in the notch, it will be against the shoulder 24 while, when this lever bears against the other end of the movable leaf, it is held in tilting position. In place of these hinge-like members there may be employed L-shaped members 28, which are pivoted at 29 to the deck, and such members may be swung on their pivots to cross the slot, or to lie clear of said slot. When lying across the slot, the upper end of the lever 21 may be held on either side of the respective member, as clearly shown in Fig. 4, in one position being locked to prevent dumping of the grate, and in the other position being locked to hold the grate dumped. Notches 30 may be provided in these levers 21 to engage the edges of the L-shaped members 28, if desired.

From the foregoing, it will be seen that

the invention provides a device which is simple in construction, but yet is efficient in operation. It will be plain to those skilled in the art that certain modifications may be made in the form and construction of the invention without departing from its material principles, and it is accordingly desired that it be understood, that not only the precise forms shown in the drawings and hereinbefore described, are to be considered as my invention, but also all modifications thereof which may fall within the scope claimed.

I claim:

- 15 1. In a grate of the class described, a main frame, alined bearings on said main frame, a dumping frame having alined journals receivable in said bearings, arms projecting downward from said bearing, said arms being provided with a plurality of spring end receiving openings, springs engaged in selected openings in said arms, means on the main frame for securing said springs thereto under tension, other arms 20 projecting downwardly from said journals, rocking levers pivoted to the main frame, and links connecting said rocking levers and the last mentioned arms.
- 25 2. In a grate of the class described, a main frame, alined bearings on said main frame, a dumping frame having alined journals receivable in said bearings, arms

projecting downward from said bearing, said arms being provided with a plurality of spring end receiving openings, springs engaged in selected openings in said arms, means on the main frame for securing said springs thereto under tension, other arms 35 projecting downwardly from said journals, rocking levers pivoted to the main frame, links connecting said rocking levers and the last mentioned arms, and means to hold the rocking levers in selected positions.

3. In a grate of the class described, a main frame, alined bearings on said main frame, a dumping frame having alined journals receivable in said bearings, arms 40 projecting downward from said bearing, said arms being provided with a plurality of spring end receiving openings, springs engaged in selected openings in said arms, means on the main frame for securing said springs thereto under tension, other arms 45 projecting downwardly from said journals, rocking levers pivoted to the main frame, links connecting said rocking levers and the last mentioned arms, means to hold the 50 rocking levers in selected positions, said means each comprising a member pivoted to the main frame and movable to swing across the path of the respective rocking lever intermediate its extreme positions.

In testimony whereof I affix my signature.
JESSE E. HANCOCK.
